UNITED STATES PATENT OFFICE.

PATRICK J. RUDDY, OF CENTRALIA, PENNSYLVANIA.

RADIORECEIVER.

Application filed March 14, 1925. Serial No. 15,491.

To all whom it may concern:

Be it known that I, PATRICK J. RUDDY, a citizen of the United States, residing at Centralia, in the county of Columbia and 5 State of Pennsylvania, have invented certain new and useful Improvements in Radioreceivers, of which the following is a specification.

The objects of my invention are to provide 10 a radio receiver which requires neither tubes, ground nor aerial and which will function efficiently when made in a size which may be carried in a pocket.

These objects, and other advantageous 15 ends which will be described hereinafter, I attain in the following manner, reference being had to the accompanying drawings in which—

Figure 1 is a diagrammatic view illustrating 20 in a general way an embodiment of my invention,

Figure 2 a perspective view of a receiver of flash-light form embodying my invention,

Figure 3 a section on line 3—3 of Figure 25 ure 2,

Figure 4 a section on line 4—4 of Figure 3, and

Figure 5 a section on line 5—5 of Figure 3.

The numeral 1 indicates an insulating tube upon which the coil 2 is wound, 3 the bar, 4 a slide mounted on the bar and carrying a brush 5 contacting with the coil, and 6 and 7 terminals. The core consists of an 30 insulating tube 8 mounted within tube 1 and providing a series of compartments 9 separated by silver plates 10. Each compartment is practically filled with metallic balls 11 preferably of uniform size, part of the 35 balls in each compartment being of steel, part of soft iron, and part of lead. I prefer to use balls in the proportion of one of steel, two of soft iron and three of lead. Insulating tube 8 is connected at its inner end with 40 a metallic cap 12 and at its outer end with a metallic cap 13. Cap 13 is pressed inwardly by a spring 14 which is held under tension by a cap 15 screw threaded on tube 1. The pressure exerted by the spring may be 45 varied by adjusting cap 15 upon tube 1 thereby varying the looseness or tightness with which the balls are held in contact. By removing cap 15 tube 8 and the contained 50 balls may be withdrawn from tube 1.

I prefer to wind the coil as shown in Figure 1, that is, reading from right to left, the

wire 16 is first wound in one direction as shown by the series of small loops to about midway of the length of the coil, then led back, as indicated by the straight line, then 60 wound in reverse direction, as indicated by the larger series of loops, and this reverse winding is continued to the left end of the coil. This provides for greater resistance within a small space than is obtained by the 65 usual method of winding.

17 and 18 indicate the batteries, 19 the usual phone cap, 20 the diaphragm, 21 a cup of insulating material secured to tube 1, and upon which the cap is screw threaded, 70 22 the electro-magnet, 23 and 24 screws taking through the cup and into plugs 24^a which take into yielding cups 25 and 26 of conducting material. Cup 26 is connected with terminal 6 by an extension 27 and cup 75 25 is connected with the batteries by an extension 28 and a threaded pin 29, 30 is a coiled spring embracing pin 29 and held between nuts 31 and 32.

I find that a magnetic core made of a plurality of magnetizable metallic bodies, free to vibrate relatively to each other, produces effects quite distinct from those produced by an integral metallic core. If, however, the core is composed entirely of magnetizable 80 bodies in contact with each other the electrical current causes them to cohere too closely and they do not vibrate with the same degree of freedom. By intermingling lead balls with the magnetizable balls the 85 latter vibrate more freely and the core becomes more sensitive to the incoming waves. While I prefer using the lead balls in about the proportion above stated, that proportion 90 may be considerably lessened without materially affecting the result.

By a series of experiments with use of different metals for the partitions forming the compartments of the core I am convinced 100 that I get better results by use of silver but am unable to assign any theory which would satisfactorily account for such a result.

Instead of housing the core and batteries in a single tube, the core might be housed in one tube and the batteries in another, the 105 tubes being disposed side by side as in an opera glass.

If the metallic balls are held too closely together or too loosely, they do not function properly, and I therefore provide the adjustable cap 15 by which the pressure may 110 be regulated.

I find that a radio receiver of small size, constructed as above described, reproduces the sound waves clearly, distinctly and effectively.

5 While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

10 Having thus described my invention, what I claim as new and desire to secure by Letters Patent is:—

15 1. A radio instrument including an insulating tube; a coil wound thereon; a metallic core, within the tube, consisting of a series of groups of metallic balls, the groups being separated by partitions of conducting material and each group consisting of a plurality of steel, soft iron and lead balls; a pair of batteries; a bar extending longitudinally of the tube; a slide mounted on the bar; a brush carried by the slide and adapted to contact with the coil; an ear-phone connected with the tube, and electrical connections between the coil, the bar, the core, the batteries, and the ear-phone.

20 2. A radio instrument including an insulating tube; a coil wound thereon, the coil being wound in reverse directions for a part of the length and in but one direction for the remainder of its length; a metallic core, within the tube, consisting of a series of groups of metallic balls, the groups being separated by partitions of conducting material and each group consisting of a plurality of steel, soft iron and lead balls; a pair of batteries; a bar extending longitudinally of the tube; a slide mounted on the bar; a brush carried by the slide and adapted to contact with the coil; an ear-phone connected with the tube, and electrical connections between the coil, the bar, the core, the batteries, and the ear-phone.

25 3. A radio instrument including an insulating tube; a coil wound thereon; a metallic core, within the tube, consisting of a series of groups of metallic balls, the groups being separated by silver partitions and each group consisting of a plurality of steel, soft iron and lead balls; a pair of batteries; a bar extending longitudinally of the tube; a slide mounted on the bar; a brush carried by the slide and adapted to contact with the coil; an ear-phone connected with the tube,

and electrical connections between the coil, the bar, the core, the batteries, and the ear-phone.

4. A radio instrument including an insulating tube; a coil wound thereon; a metallic core, within the tube, consisting of a series of groups of metallic balls disposed in a second insulating tube, the groups being separated by partitions of conducting material and each group consisting of a plurality of steel, soft iron and lead balls; a pair of batteries; a bar extending longitudinally of the tube; a slide mounted on the bar; a brush carried by the slide and adapted to contact with the coil; an ear-phone connected with the tube, and electrical connections between the coil, the bar, the core, the batteries, and the ear-phone.

5. A radio instrument including an insulating tube; a coil wound thereon; a metallic core, within the tube, consisting of a series of groups of metallic balls, the groups being separated by partitions of conducting material and each group consisting of a plurality of steel, soft iron and lead balls; means for regulating the pressure of the balls; a pair of batteries; a bar extending longitudinally of the tube; a slide mounted on the bar; a brush carried by the slide and adapted to contact with the coil; an ear-phone connected with the tube, and electrical connections between the coil, the bar, the core, the batteries, and the ear-phone.

6. A radio instrument including an insulating tube; a coil wound thereon; a metallic core, within the tube, consisting of a series of groups of metallic balls disposed in a second tube slidable in the main tube, the groups being separated by movable partitions of conducting material, each group consisting of a plurality of steel, soft iron and lead balls; metallic caps closing the ends of the second tube, one of the caps being slidable relatively to the tube; an adjustable cap on the end of the main tube; a spring mounted between the adjustable cap and the slidable cap; a pair of batteries; a bar extending longitudinally of the tube; a slide mounted on the bar; a brush carried by the slide and adapted to contact with the coil; an ear-phone connected with the tube, and electrical connections between the coil, the bar, the core, the batteries, and the ear-phone.

In testimony whereof I have signed my name to this specification.

PATRICK J. RUDDY.
